CLAIM

We claim the ornamental design for an LED light, as shown and described.

DESCRIPTION

FIG. 1 is a perspective view of the LED light of the present invention;

FIG. 2 is a top view of the LED light of the invention shown in FIG. 1;

FIG. 3 is a right side view of the LED light of the invention shown in FIG. 1, with the left side view being a mirror image thereof; and,

FIG. 4 is a bottom view, of the LED light of the invention shown in FIG. 1.

The broken lines depict features of the article that form no part of the claimed design.

1 Claim, 3 Drawing Sheets
